UNITED STATES PATENT OFFICE.

GEORGE J. WILLETT, OF MILWAUKEE, WISCONSIN.

CAR-COUPLING.

1,140,223.

Specification of Letters Patent. Patented May 18, 1915.

Application filed September 19, 1914. Serial No. 362,481.

To all whom it may concern:

Be it known that I, GEORGE J. WILLETT, a citizen of the United States, and resident of Milwaukee, in the county of Milwaukee and State of Wisconsin, have invented certain new and useful Improvements in Car-Couplings, of which the following is a specification.

My invention relates to car couplers of the type known as the arrow head and has particular reference to a novel, automatic centering mechanism for use in connection therewith.

In many manufacturing establishments, mines, yards, etc., a series of cars will be employed which are not adapted for interchange traffic with standard railways and are intended for use solely in connection with the particular establishment owning the cars. Such cars may be of light construction and operated on other than standard gage tracks. However, coupling means must be provided for the cars and as the loads are not great nor the requirements severe, a coupler of the arrow head type may be used to advantage in preference to one of the M. C. B. type. It is to a coupler of the arrow head type that this invention particularly relates the improvement residing in the means employed for automatically centering the coupling member without the use of springs or other elements which might become weakened or broken.

The invention will be more readily understood by reference to the accompanying drawings, wherein,

Figure 1 is a side elevation of a car coupler constructed in accordance with my invention, and, Fig. 2 is a plan view of the same.

In the drawings the head of the coupler is indicated at 10, and includes upper and lower shelves 11, 12, between which the coupling member of a mating device may be accommodated. Lateral flanges 13, on the head provide means for attachment of the coupler to a wall 14, or other portion of the car. The head 10, is vertically apertured to accommodate a pivot pin 15, which pin provides the pivot for the coupling member or knuckle 16. The shank 16 of this member terminates in an arrow head 17, which may

be of any desired shape in order to properly engage with the mating head. This pivot pin preferably engages the shank 16, through a squared aperture in order that the pin may move with the coupling member. Above the head 10, and also pinned to the pivot 15, is a hand lever 18, by means of which the coupling member may be manually shifted. The rear portion of the shank 16 extends into a recess 19, formed in the head 10, the shank being bifurcated as at 20, a link 21, extending between the bifurcations and being pivotally held by means of a pin 22. The opposite end of the link 21 is apertured and accommodates a stud 23, forming a portion of a bell crank 24, pivoted at 25, to a bracket member 26, secured to the wall 14. The bell crank is provided with a weight 27, on its free arm.

The operation is as follows: The parts being assembled as shown, the bell crank exerts tension on the link 21, and tends to straighten out any deflection of the coupling member until the axes of the pins 15, 22, 23, are in alinement. When the arrow head is shifted to one side as will occur when the coupling operation is effected, the weight will be lifted but there is a constant tendency toward the bringing of the arrow head into longitudinal alinement with the bell crank.

The parts are very simple and will not readily become out of order and as no springs are employed the objection to breakage along that line is overcome.

The parts may be modified to a certain extent all without departure from the spirit of my invention.

I claim:

1. In a coupler, the combination of a recessed head, an arrow head coupling member pivoted in said head at a point intermediate of the length of the coupling member, a link pivoted to the rear end of said member, and a weighted bell crank acting upon said link and tending to maintain said link and coupling member in alinement, substantially as described.

2. In a coupling device, the combination of a pocket, a coupler pivoted therein, a link pivoted to the rear of the coupler and in line therewith, and a weighted bell-crank pivot-

ed at the rear of the pocket and directly connected to said link, substantially as described.

3. In a coupling device, the combination of a pocket, a coupler having a fixed pivot in said pocket, a link connected to said coupler and normally in alinement therewith, and a weighted bell-crank pivoted on a

transverse horizontal pivot at the rear of the pocket and directly connected to said link, substantially as described.

GEORGE J. WILLETT.
